Des. 228,214
Patented Aug. 28, 1973

228,214

STUDY MODULE

Lawrence J. Michiels, 2060 Cedar St.,
San Carlos, Calif. 94070

Filed Aug. 16, 1971, Ser. No. 172,370

Term of patent 14 years

Int. Cl. D6—06

U.S. Cl. D6—157

FIG. 1 is a perspective view showing the front and right and left side walls of a study module;

FIG. 2 is a top plan view;

FIG. 3 is a front plan view;

FIG. 4 is a right side plan view;

FIG. 5 is the left side view;

FIG. 6 is a bottom plan view; and

FIG. 7 is a plan view of the rear side of the study module shown at one-half scale.

I claim:

The ornamental design for a study module, as shown.
